DESIGN FOR AN ELECTRIC MOTOR GENERATOR

Edward J. Petry, Jefferson City, Mo.

Application May 8, 1947, Serial No. 138,903

Term of patent 14 years

(Cl. D26—5)

To all whom it may concern:

Be it known that I, Edward J. Petry, a citizen of the United States, residing at Jefferson City, in the county of Cole and State of Missouri, have invented a new, original, and ornamental Design for an Electric Motor Generator, of which the following is a specification, reference being had to the accompanying drawing, forming part thereof.

Figure 1 is a perspective view of an electric motor generator, showing my new design.

Figure 2 is a perspective view illustrating the opposite side of Figure 1.

I claim:

The ornamental design for an electric motor generator, as shown.

EDWARD J. PETRY.
